UNITED STATES PATENT OFFICE.

LE ROY T. STEWARD, OF CHICAGO, ILLINOIS.

RECEPTACLE FOR MAIL AND THE LIKE.

1,104,153.

Specification of Letters Patent. Patented July 21, 1914.

Application filed August 31, 1912. Serial No. 718,007.

To all whom it may concern:

Be it known that I, LE ROY T. STEWARD, a citizen of the United States, residing at Chicago, county of Cook, State of Illinois, have invented a certain new and useful Improvement in Receptacles for Mail and the like, and declare the following to be a full, clear, and exact description of the same, such as will enable others skilled in the art to 10 which it pertains to make and use the same, reference being had to the accompanying drawings, which form a part of this specification.

The means generally provided in residences, office buildings, and other places where mail is delivered by mail carriers is more or less of a makeshift, being inadequate in that magazines, books or other large pieces of mail, inflexible in character or 20 bulky in form, cannot be received thereby, and must therefore be left exposed, be taken back to the post office and the delivery indefinitely delayed, or be delivered into the hand of the tenant who must be called perhaps from some remote point such as an 25 upper floor of an apartment building; being unsafe, in that usually it is possible for unauthorized persons to extract mail therefrom and giving no protection whatever to the 30 larger pieces of mail; permitting the owners or users to be subjected to annoyance on account of undesired, useless and often objectionable advertising matter being deposited by wandering peddlers or bill distributors, such matter not only causing embarrassment and annoyance on account of its 35 very nature, but often concealing legitimate mail so that the presence of the latter is not detected by the owner. Furthermore, most 40 mail-receiving receptacles are not sanitary because they have openings through which dust and dirt may at all times enter, such dust and dirt collecting in the receptacles and making them foul.

45 The primary object of my invention is to produce a receptacle for mail or other similar matter which shall be free from the objections which I have just enumerated.

50 A further object of my invention is to produce a novel receptacle which may be used both as a delivery box and a collection box.

55 A further object of my invention is to produce a receptacle for mail matter which will make it easy for a mail carrier to introduce mailed matter of any description, thus

greatly reducing the labor of the carrier and enabling him to do his work most expeditiously.

The various features of novelty whereby 60 my invention is characterized will herein-after be pointed out with particularity in the claims; but for a full understanding of my invention and of its various objects and advantages, reference may be had to the following detailed description taken in connection with the accompanying drawing, 65 wherein:

Figure 1. is a perspective view of a receptacle arranged in accordance with a preferred form of my invention, the receptacle being shown in its closed position; and Fig. 2 is a view similar to Fig. 1, showing the receptacle open for receiving mail or other material.

In carrying out my invention I make use of a receptacle which is normally completely closed, at least on the side which may be approached by unauthorized persons, and is so constructed that it may be opened only by 70 one having a proper key or combination, either for depositing matter in the receptacle or removing it therefrom. I prefer to provide each receptacle with two locks, one for the user and one for the mail carrier, the latter lock being preferably the same on all 75 the receptacles in a given city or district so that the carrier, with a single key, can quickly open all of the boxes on his route.

Where there are a number of receptacles 80 placed together as, for instance, in apartment houses, I prefer so to construct the receptacles that a whole battery of receptacles may be opened simultaneously by the carrier, thus placing all of them in condition 85 freely to receive mail and permitting the distribution to be quickly effected. Then after the mail has been deposited in the proper boxes or receptacles, they may all be closed in a single operation.

It is often desirable as, for example, in 90 large apartment houses, to have the collection boxes easy of access to the tenants and, in such case, chutes leading to the several receptacles may be provided so that the tenants may drop out-going mail into their own receiving-receptacles or boxes from any convenient points. Then the carrier, after 95 opening the boxes or receptacles, first removes the out-going mail therein before distributing his mail.

In the drawings I have illustrated only a

single form of my invention as embodied in a nest or battery made up of three mail boxes or receptacles and, for the sake of brevity, I shall confine the detailed description to this specific arrangement; but it will of course be understood that I do not desire to be limited to the particular construction and arrangement illustrated or to the use of my improved device as a mail-receiving receptacle, since in its broader aspects my invention may take various other specific forms and be used for other purposes than for receiving mail only.

Referring now to the drawings, 1 represents a suitable frame extending around one end of a battery of connected boxes or receptacles, 2, 3 and 4, lying side by side. The receptacles are hinged to the frame at the bottom, as indicated at 5 and have a flange 6 which is adapted to engage with the top and two sides of the frame to limit the backward swinging movement of the receptacles. If desired, the frame may have on the back thereof a casing or housing 7, which incloses the receptacles when they are swung back so as to bring the flange into engagement with the frame. The casing or housing is not, however, essential. The tops of the receptacles are open so that when the receptacles are swung out as shown in Fig. 2, mail matter or other articles small enough to fit into the receptacles may readily be inserted. By this arrangement, making the receptacles large enough to receive magazines, ordinary books, and other matter customarily sent through the mails, every piece can be placed in one of the receptacles and need not be left on the outside as is now commonly done by the carrier. Each receptacle is provided with a door, as indicated at 8, 9 and 10 respectively, the doors being large enough to permit the removal of any article which can be placed in one of the receptacles. Near the top of the nest or battery of receptacles is a knob or handle 11 which may also serve as a part of a lock having a key-receiving slot or opening 12. The lock may be of any suitable form which will securely hold the battery of receptacles in a closed position except when released by a suitable key or by manipulating a proper combination device. Each of the doors, 8, 9 and 10 is also provided with an individual lock, as indicated at 14, 15 and 16 respectively. The main lock is intended to be under the control of the mail carrier while each of the other locks is under the control of the proper tenant, owner or user.

The device is mounted in or on a wall, door or other suitable place which will permit the mail carrier to have access to it. A convenient method of mounting the device, (although any desired method may be employed,) is to make an opening in a wall of the building and secure the device in the

opening with only the front face of the frame and the front of the receptacle exposed.

Normally the receptacles are closed so that nothing can be put into them or taken out of them except by authorized persons having the proper keys or combinations. When the mail carrier comes, he opens the main lock, the receptacles are swung out as shown in Fig. 2, the mail is quickly inserted into the receptacles, and then the receptacles are swung back in their normal closed position; the entire operation being quickly performed and all of the mail being quickly and securely housed in the proper receptacles.

To remove the mail from his receptacle, the tenant or owner simply unlocks the proper door, thus giving him access to the contents of the receptacle; and, by making the doors of the proper size and shape, any piece of mail or other article which may be placed in a receptacle may be taken out through the door of that receptacle.

Since it is easier for the carrier to swing the receptacles in the closing direction than to pull them open, a suitable spring or springs 17 may be placed beneath or behind the receptacles in position to swing the receptacles out whenever the main lock is unfastened, so that as soon as the carrier unlocks the receptacles they are swung into their receiving position and no time is lost in opening them or holding them in the open position. After the mail has been deposited in the receptacles, the latter are closed by simply giving them a backward push.

Where the receptacles are to serve also as collection boxes, suitable chutes, whose outlet ends are indicated at 18 to 20, respectively, may be led from suitable points within convenient reach of the users, each chute terminating just above the proper receptacle. By this arrangement, mail for collection may be placed in the receptacles and the carrier, before distributing his mail, can take from the receptacles mail left for collection.

It will thus be seen that I have produced a simple, novel and efficient device in which all articles or things ordinarily sent through the mails may be placed by the carrier so that nothing need be left in an exposed position; that no unauthorized person can either insert or remove any article of any kind from the receptacle; that because no openings are normally left, dirt is excluded from the receptacle so that it and its contents remain clean and wholesome; that a simple means is provided for depositing mail for collection; and that the time and energy of the mail carrier are conserved by reason of the ease with which he can deposit the mail to be delivered.

While I have illustrated and described with particularity only a single preferred embodiment of my invention, I do not de-

sire to be limited to the specific structural details thus illustrated and described; but intend to cover all forms and arrangements which fall within the terms employed in the 5 definitions of my invention constituting the appended claims.

I claim:

1. A device for holding mail or the like comprising a plurality of connected receptacles open at the top, a closing device for said open tops, means for mounting said receptacle so as to permit it to be moved into and out of operative relation to said closing device, a lock for holding said receptacles 10 in operative relation to said closing device, independent doors in said receptacles, and independent locks for said doors adapted to permit each of said doors to be opened independently of the others.
2. A device for holding mail or the like, comprising a casing open on the front side, a receptacle arranged in said casing and forming a closure for said open side, a hinge connecting the lower front corner of the receptacle to said casing, said receptacle being open at the top and having a series of vertical partitions extending from the top to the bottom thereof to divide it into a series 15 of compartments, a lock arranged to lock the receptacle in position wherein the top thereof is closed by the casing, each of said compartments having an individual door in the front wall of the receptacle, and separate locks for said doors.
3. In a device for holding mail or the like, 20
- 35

a casing open at the front, an open-top receptacle arranged in the casing and having a front wall of the size and shape to close the open side of the casing, said receptacle being open at the top, a series of vertical 40 partitions arranged in the receptacle to divide it into a series of compartments, a hinge connecting the lower front corner of the receptacle to the casing, a spring acting on the receptacle to swing the upper end outwardly and expose the open upper ends of the compartments, a lock for holding the receptacle in its retracted position with the upper end closed by the casing, separate doors in the front wall of the receptacle for 45 said compartments, and a lock for each door.

4. A device for holding mail or the like comprising a casing open on one side, a receptacle divided into a series of individual 50 compartments, all of said compartments being open on one side of the receptacle, each compartment being provided with a door in a side of the receptacle adjacent to the open side, means for movably supporting the receptacle in the casing, a lock for locking the receptacle in the casing and individual locks for said doors.

In testimony whereof, I sign this specification in the presence of two witnesses.

LE ROY T. STEWARD.
